CATCHUP DISPENSER

Frank Damiano, Newburgh, N. Y.

Application October 4, 1948, Serial No. 52,685

2 Claims. (Cl. 222—323)

1

This invention relates to new and useful improvements and structural refinements in dispensers for catchup, mustard, and other materials of a semi-fluid consistency, and the principal object of the invention is to facilitate dispensing of such materials in a convenient manner and in properly-regulated amounts or at a well-regulated rate of flow, as the case may be, thereby avoiding the conventionally experienced necessity of inverting and violently shaking the container, the undesirable consequences of which are well known.

This object is achieved by the provision of a dispenser which, broadly speaking, includes a container, a dispensing spout and means for efficiently delivering material from the container through the spout in such manner that the hands of the operator do not come in contact with the spout or the container.

An important feature of the invention resides in the provision of means for predetermining the amount of material dispensed in one operation.

An important advantage of the invention resides in its simplicity of construction, in its pleasing appearance, and in its adaptability to economical manufacture.

An additional advantage resides in the provision of a dispenser which may be easily kept clean and wherein the supply of material, when exhausted, may be quickly and easily replenished.

With the above more important objects and features in view and such other objects and features as may become apparent as this specification proceeds, the invention consists essentially of the arrangement and construction of parts as illustrated in the accompanying drawings, in which:

Figure 1 is a vertical cross-sectional view of the invention;

Figure 2 is a cross-sectional view, taken substantially in the plane of the line 2—2 in Figure 1;

Figure 3 is a cross-sectional view, taken substantially in the plane of the line 3—3 in Figure 2;

Figure 4 is a vertical cross-sectional view of a modified embodiment of the invention;

Figure 5 is a cross-sectional view, taken substantially in the plane of the line 5—5 in Figure 4; and

Figure 6 is a perspective view of a handle used in the embodiment shown in Figure 4.

Like characters of reference are employed to designate like parts in the specification and throughout the several views.

2

Referring now to the accompanying drawings in detail, more particularly to Figures 1, 2 and 3, the invention consists of a dispenser for catchup, mustard, and similar semi-fluid materials, the dispenser being designated by the general reference character 10 and embodying in its construction a substantially cylindrical body 12 provided in the upper portion thereof with a recess 14 having a bottom wall 16 declining to a substantially rectangular opening 18, whereby the recess 14 communicates with a horizontally elongated well or chamber 20 provided in the lower portion of the body 12.

The upper edge portion of the recess 14 is internally screw-threaded as at 22 to accommodate a complementarily screw-threaded neck portion 24 of a suitable container 26, a suitable gasket 28 being provided at the lower edge of the neck, for obvious reasons. Moreover, it is to be noted that the upper end of the container 26 terminates in a screw-threaded filler neck 30, equipped with a removable cap or cover 32.

The entire dispenser rests upon a plurality of legs 34 provided on the body 12, and an upwardly extending strap-like handle 36 is secured to the body as at 38 so that the entire dispenser may be easily carried from one location to another.

One end of the well 20 is provided with a removable plug 40 which is secured to the body 12 as at 42, this plug being equipped with a seal 44 and providing a bearing for a slidable rod 46, to the inner end of which is, in turn, secured a piston 48 by a screw 50. The piston 48 is reciprocable in the well 20 and the rod 46 projects outwardly substantially as shown.

An actuating lever 52, equipped with a suitable finger-piece 54, is pivotally connected at one end thereof as at 56 to the upper end of the handle 36, while the lower end of the lever is operatively connected by a pin and slot connection 58, 60 to the outer end of the rod 46. Moreover, a suitable leaf spring 62 is interposed between the handle 36 and the lever 52, being secured to the handle as at 64.

A passage 66 is provided in the body 12, this passage extending upwardly and outwardly from an end portion of the well 20 opposite to that equipped with the plug 40, and an upwardly extending conduit 68 is secured at its lower end in the passage 66, being provided at its upper end with an arcuated spout 70. If desired, a pivoted cover or cap 72 may be provided on the spout 70, so as to seal the conduit 68 and the well 20 from the atmosphere.

When the invention is placed in use, the container 26 is simply filled with catchup, or the

like, through the medium of the filler neck 36, the catchup gravitating into the recess 14 and through the opening 48 into the well 28, as will be clearly apparent. Thereupon, by simply pressing the lever 52 toward the handle 36, the piston 48 will be caused to slide in the well 28 as shown at 74 and catchup will be expelled from the well through the passage 66, conduit 68 and the spout 78. It should, of course, be understood that the pivoted cover 72 is pressure-actuated, so to speak, becoming automatically opened by the force of the material being dispensed.

After pressure on the lever 52 is released, the spring 62 will return the lever to its initial position. If desired, a stop screw 76 may be provided on the body 82 and arranged to extend into the well 28 as shown, so as to limit the inward sliding movement of the piston 48. In this manner, the volume of material dispensed during one stroke of the piston may be pre-adjusted as desired.

Referring now to the accompanying Figures 4, 5 and 6, these illustrate a modified embodiment of the dispenser, designated generally by the reference character 88 and embodying in its construction a substantially oval-shaped body 82 formed with a well 84 which extends inwardly into the body substantially as shown and is internally screw-threaded at the outer end thereof, as at 86, so as to receive a screw-threaded neck portion of an inverted container 88. This container may be of any conventional type, such as for example, that in which the catchup, mustard, or the like, is supplied to the purchaser.

It is to be noted that a recess 90 exists in the lower portion of the body 82 under the well 84, and a vertically disposed pump cylinder 92, having a screw-threaded lower end portion 94, is secured in the well 84, with its lower end portion projecting into the recess 90, as shown. The bottom wall 96 of the well 84, apart from being provided with a circular opening to accommodate the cylinder 92, is formed with a plurality of notches 98 at the edge of the cylinder-receiving opening, while the lateral wall of the cylinder 92 is equipped with a plurality of outwardly projecting lugs 100 which pass through the notches 98.

By virtue of this construction, the cylinder 92 may be easily installed by simply being passed upwardly from the recess 90 into the well 84 with the lugs 100 passing through the notches 98, and after the cylinder is in its proper position, it may be rotated to some extent in one direction or the other, so that the lugs 100 are seated upon the bottom wall 96 of the well 84, thus retaining the cylinder in position.

Moreover, a clamping nut 102, provided with a gasket 104, is positioned on the screw-threaded portion 94 of the cylinder 92, so that by tightening the nut 102, the gasket 104 may be urged against the under-surface of the well bottom 96, to retain the cylinder in place.

The upper end of the cylinder 92 is formed integrally with a tubular extension 106 which projects upwardly through the upper wall 108 of the body 82, and a substantially U-shaped handle 110, provided with a pair of eyes 112, is secured on the extension 106 by means of a suitable nut 114, as will be clearly apparent.

A reciprocable piston rod 116, provided on its upper end portion with a tubular guide 118, is slidable (together with the guide) in the tubular extension 106, the upper end of the piston rod 116 carrying a suitable finger piece 120, where-

by the piston rod may be pressed downwardly with the thumb, the user's hand grasping the handle 110.

A piston 122 is secured to the lower end of the rod 116, and a compression spring 124, disposed in the extension 106, normally urges the piston 122 toward the upper end of the cylinder 92.

A screw-threaded cap 126 is secured at the lower end of the cylinder 92 and an adjusting screw 128 is provided in this cap, for the purpose of limiting the extent of downward travel of the piston 122. The cap 126 also provides a dispensing passage 130 terminating in a screw-threaded nipple 132 to which is connected by means of a suitable coupling member 134, an outwardly and upwardly extending dispensing conduit 136. It is to be noted that this conduit terminates in a laterally arcuated spout 138 provided with a pivoted cap or closure 140, similar to the aforementioned cover 72.

The conduit 136 extends outwardly from the recess 90 through a suitable aperture or opening 142 provided in the body 82, and it is to be noted that the body is also equipped with a plurality of suitable legs 144, on which the entire dispenser may rest.

Finally, it should be explained that the lateral wall of the aforementioned cylinder 92 is formed with a plurality of apertures or passages 146, which connect the interior of the cylinder with the well 84.

When the invention is placed in use, the container 88, filled with mustard, or the like, is simply installed in an inverted position on the body 82, so that the contents thereof may gravitate into the well 84 and through the apertures 146 into the cylinder 92.

Thereupon, by simply pressing the finger piece 120 downwardly, the piston 122 will force the catchup in the cylinder 92 through the passage 130 and through the conduit 136, as will be clearly apparent. The amount of material dispensed in each operation may be predetermined by simply adjusting the screw 128, so as to limit the extent of downward movement of the piston 122, thus varying its displacement accordingly.

Needless to say, the construction of the dispenser 88 as described facilitates convenient disassembly thereof for purposes of cleaning, and it may be added at this point that the dispenser 10 may be disassembled with equal expediency, the piston 48 thereof being accessible for cleaning purposes by simply removing the aforementioned plug 40.

It is believed that the advantages and use of the invention will be clearly apparent from the foregoing disclosure, and, accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a dispenser of the character described, the combination of a hollow body affording a well and including a top wall and a bottom wall, said bottom wall being provided with a circular opening and with a plurality of spaced notches at the edge of said opening, a vertical pump cylinder including a top and a lateral wall hav-

ing a foraminous upper portion and an externally screw-threaded lower portion, a plurality of circumferentially spaced and outwardly projecting keeper lugs provided intermediate the ends of said lateral wall and receivable in said notches, said cylinder projecting through said opening into said well and said lugs engaging the upper surface of said bottom wall, a keeper nut provided on said lateral wall under said bottom wall, a removable cap provided at the bottom of said cylinder and having an internally screw-threaded marginal flange engaging said lateral wall, said cap being provided with an outlet passage, a piston reciprocable in said cylinder, and means provided at the top of the cylinder and projecting upwardly through said top wall for reciprocating said piston.

2. The device as defined in claim 1 wherein said top wall is provided with an aperture coaxial with said opening, said means comprising a tubular member extending upwardly from the top of said cylinder through said aperture, a substantially U-shaped handle having free end portions thereof provided with a pair of eyes positioned at vertically spaced points on said

5 10 member, a nut provided on said member and urging the lower of said eyes against the upper surface of said top wall, a spring pressed plunger slideable vertically in said member and connected at its lower end to said piston, and a finger piece provided at the upper end of said plunger for coaction with said handle.
